UNITED STATES PATENT OFFICE

2,656,620

WELTED MOCCASIN

Earl Thomas Taylor, Beloit, Wis.

Application January 12, 1953, Serial No. 330,631

2 Claims. (Cl. 36—17)

1

My invention relates to moccasins and more particularly to a welted moccasin.

One of the objects of my invention is to provide a shoe structure which combines the casual appearance and comfort of a moccasin but having a firm but still flexible sole portion.

Another object of my invention is in the combination of a moccasin formed upper with a welted and flexible sole portion forming a welted moccasin.

Yet another object of my invention is in the formation of a welted moccasin formed by connecting an insole, having a flexible insert, with the sole by means of a welted connection.

A further object of my invention is in the combination of a moccasin sewn upper affixed to the sole by means of a welted construction which includes stitching of the welt to the sole and upper and a specially formed flexible insole.

Other objects will appear when the following specification is considered in connection with the attached drawing in which:

Fig. 1 is a perspective view of the welted moccasin;

Fig. 2 is a vertical sectional view showing the manner of fabricating the welted moccasin;

Fig. 3 is a sectional view taken along the line *a—a* of Fig. 2; and

Fig. 4 is a sectional view taken along the line *b—b* of Fig. 2.

Referring specifically to the drawings, we find in Fig. 1 a view showing the outward appearance of the finished welted moccasin. It is immediately apparent the applicant's structure has the general casual appearance of the well-known moccasin type of foot gear.

Stitching 10 joins the toe plug 11 with the vamp 12 to form the moccasin sewn upper 13a having a quarter 13.

The instep is crossed by fixedly sewn strap 14 and flexible, resilient leather strips 15 are sewn thereto at 14a. Strips 15 are further sewn to the toe plug at 30 and extend parallelly upwards to terminate in undeturned ends 15a which are sewn to an elastic lining 16a by means of stitching 16. The strips 15 are also preferably stitched to lining 16a substantially throughout their lengths by means of longitudinal stitching, not shown. The outermost strips 31 and 32 are further longitudinally stitched to the edges of the upper at 33 and 34, and the elastic lining is secured to the upper assembly by means of its longitudinal stitching to strips 31 and 32. The elastic lining 16a may be further fastened to strips 15 by means of an elastic adhesive.

Strapping of the instep could be accomplished, of course, in any number of ways.

The moccasin upper 13a is connected to welt 17 and specially formed insole 18 by means of stitching 19 as clearly shown in several of the figures in the drawings.

Insole 18 has its lower portion formed at 20

2

to receive a flexible treated cork insert 21 which fills the space between the insole and sole 22.

A narrow corrugated stiffened metal strip 23, disposed under the insole 18, is imbedded in the treated flexible insert 21 in a manner to form an arch support, but at the same time permit the degree of flexibility required in this type of foot gear.

The sole 22 is stitched at 25 to the welt 17.

Heel 26 is nailed as at 27 to the sole 22 in the usual manner.

The liner consisting of the toe plug liner 28, instep liner 16a, and main liner 29 is cemented and sewn within the moccasin in the usual manner.

Applicant's welted moccasin construction is completed by cementing the heel and arch seat 30 over the rear portion of the liner.

This application is a continuation in part of my copending application Serial No. 180,330, filed August 19, 1950, now abandoned.

I claim:

1. A welted moccasin comprising a moccasin type upper including a vamp and quarter, a toe plug sewn to said vamp and an instep portion comprising flexible resilient leather strips attached to said toe plug, an insole having outer depending flanges having lower edges contacting and coinciding with the lower edges of said upper, a flexible insert within and filling the space within the flanges of said insole, a welt stitched to the lower edges of the upper and to the lower edges of the insole, an outsole stitched to the welt, and a continuous one layer liner stitched to the upper edges of the quarter and to the vamp and the toe plug and covering all of the upper surface of said insole and all of the inner surface of the quarter and vamp portion of said upper.

2. A welted moccasin comprising a moccasin type upper including a vamp and quarter, a toe plug sewn to said vamp and an instep portion comprising flexible resilient leather strips attached to said toe plug, an insole having outer depending flanges having lower edges contacting and coinciding with the lower edges of said upper, a flexible insert within and filling the space within the flanges of said insole, a welt stitched to the lower edges of the upper and to the lower edges of the insole, an outsole stitched to the welt, a continuous one layer liner stitched to the upper edges of the quarter and to the vamp and the toe plug and covering all of the upper surface of said insole and all of the inner surface of the quarter and vamp portion of said upper, an elastic lining member covering the inner surface of said instep portion, and means securing said resilient leather strips to said elastic lining.

EARL THOMAS TAYLOR.
